UNITED STATES PATENT OFFICE

136,043

DESIGN FOR A FULL OPENING LIGHTER

Alexander Sydney Weston, New York, N. Y.

Application April 3, 1942, Serial No. 106,442

Term of patent 14 years

To all whom it may concern:

Be it known that I, Alexander Sydney Weston, a citizen of the United States, residing at 85 East 10th Street, New York, N. Y., in the county of New York and State of New York, have invented a new, original, and ornamental Design for a Full Opening Lighter, of which the following is a specification, reference being had to the accompanying drawings, forming a part thereof.

In the drawings:

Fig. 1 is a front elevational view showing my novel design of a full opening lighter.

Fig. 2 is a rear elevational view thereof.

Fig. 3 is a rear elevational view in an open position, and

Fig. 4 is a top plan view thereof.

The characteristic features of my design reside in the combination of a flat oval lighter, a U-shaped pivot lug at the one end of its top, a hammer head arm pivoted therein, and an oblique oval widening hood secured on the head, as shown.

I claim:

The ornamental design for a full opening lighter, as shown and described.

ALEXANDER SYDNEY WESTON.
